Filed Apr. 17, 1956, Ser. No. 578,836

7 Claims. (Cl. 103—120)

This invention relates to an arrangement functioning as pump or motor, which consists of a drive gear and a follower gear meshing with each other and working in a casing provided with inlet and outlet for an operating medium. Actually the invention refers to a design according to which the mesh of the teeth of the gears may be varied.

The most characteristic feature of the invention is a shaft (the adjustment shaft) rotating in the casing provided with an eccentric bearing surface for the rotating gear located on said surface so that by rotating the adjustment shaft in the casing the spacing of the gears may be varied while maintaining a seal between the outer periphery of the follower gear and the casing. Thus the teeth of the gears always mesh with a minimum of play between them.

Previously it has been proposed to design gear pumps in such a manner that the mutual mesh between the teeth feeding the operating medium may be varied. In one known design the shafts of the gears are supported independently of each other, each one in a separate pair of discs, whereas the casing is divided into two halves variable as to the shaft spacing. The pairs with their gear bearings are moved by means of adjusting screws in relation to each other, thus making it possible to vary the gear mesh. This arrangement is not satisfactory from a sealing point of view and can not be readjusted during operation.

In another known design the follower gear is inserted eccentrically into a disc resembling the shape of a crescent which can be rotated from the outside. By rotating the disc it is possible to vary the play between the gear teeth. Through such variation of the play it was possible to readjust the pump capacity, when the variation in capacity to a great extent would result from leakage, due to the fact that the follower gear is lacking proper support. This design is in the first place intended for the adjustment of minimum play between the gears. The degree of the play will vary with the eccentricity and the pump volumetric efficiency will vary with the play. Play will arise also between the follower gear and the inner wall of the disc functioning as a guide, for which reason this design in the first place is intended only to improve the mesh to compensate for wear. In addition the design is difficult to manufacture as well as expensive.

Designs of gear pumps of variable capacity known up to now have been limited to those provided with gears of the external tooth type, but as will be evident from the following description of some alternatives of the invention, this can also be applied to advantage in designing gear pumps and motors of the internal tooth type respectively.

In the accompanying drawings a number of designs of the invention are shown only as examples without any further limitation.

Fig. 1 shows a perspective view of an arrangement ac-

2

cording to the invention with gears of the external tooth type.

Fig. 2 shows a perspective view of the arrangement according to Fig. 1 with one end of the casing removed showing the gears in full mesh.

Fig. 3 shows a perspective view similar to that in Fig. 2 with the gears removed from each other.

Fig. 4 shows schematically the profile of the internal outline of the wall part of the casing which surrounds the follower gear.

Fig. 5 shows a cross-section taken along the line 5—5 in Fig. 6 through another arrangement according to the invention with the drive gear of internal tooth type and the follower gear installed inside the former when the gears are fully in mesh with each other.

Fig. 6 shows a vertical section according to the line 6—6 in Fig. 5.

Fig. 7 shows a section along the line 7—7 in Fig. 5.

Fig. 8 shows a radial detail section along the direction indicated by the line 8 in Fig. 5.

Fig. 9 shows an end view taken in the direction indicated by the line 9 in Fig. 6.

Fig. 10 shows a cross-section similar to that in Fig. 5 with the gears removed a maximum distance from each other.

Fig. 11 shows in perspective view partly broken away a further modification of an arrangement with internal gear as in Figs. 5—10 but with pierced tooth bases in the external gear race of internal tooth type.

Fig. 12 shows a cross-section through the last-mentioned arrangement.

Figs. 13 and 14 show further modified design details included in the invention.

Fig. 15 shows a diagram of the pressure rise as a function of the RPM of the arrangement according to the invention operating as a pump.

Fig. 16 shows schematically a control system for the arrangement firstly operating as a pump (full-drawn lines), secondly as a motor (dashed lines).

Fig. 17 shows schematically the arrangement equipped with a control system in connection with the application of the arrangement as a pump, by means of which control system the pressure regulating range of the pump allows itself to be varied.

Fig. 18 shows schematically a control system of modified design when the arrangement is applied as a motor.

Fig. 19 shows schematically an additional modified design of a control system when the arrangement is applied as a pump.

The arrangement shown in Figs. 1—4 consists of two gears 20, 22 of external tooth type located side by side in a casing 24 which is provided with ducts 26, 28 for inlet and outlet of the operating medium. The axle shaft of the drive gear 20 is indicated by 30. The follower gear 22 is located on a bearing surface 34 which is eccentric in relation to an adjustment shaft for this gear. The bearing surface is located on said shaft. The adjustment shaft 32 is supported in the casing extending through one end 36 of the same by means of a journal 38. By means of this journal 38 the adjustment shaft 32 will actuate either by the application of positive force or by self-adjustment against a spring force. Due to the eccentric support of the follower gear 22 a displacement of the rotating center of the follower gear 22 is obtained by rotating the adjustment shaft 32 along an arc in such a manner that this gear in one limit stop is in full mesh with the drive gear 20 and in the other limit stop is only in mesh sufficiently to maintain constant rotation of the follower gear 22. The tooth addendums of the drive gear 20 contact the inner surface 40 of the casing half 42 contacting said addendums without play as much as pos-

sible whereas the inner surface 44 of the other casing 46 surrounding the follower gear 22 is generated in the following manner.

Referring to Fig. 4, 48 constitutes the center of the adjustment shaft 32 and the rotation center 50 of the follower gear 22, which is movable along an arc with the radius r from one extreme limiting position 50, in which the gears are in maximum mesh giving maximum capacity, to a second extreme limiting position 50' in which the gears are in minimum mesh giving minimum capacity. Accordingly the adjustment shaft 32 will revolve about its center 48 within the angle of radii 48-52 and 48-52', and the enveloping surface 44 comprises three cylindrical areas 54-52, 52-52' and 52'-56. The first cylindrical area 54-52 has a radius slightly greater than the radius R of said follower gear and a center of curvature coinciding with the center 50 of the follower gear 22 when in its extreme limiting position for maximum mesh. The portion 54-52 extending from the high pressure port has a length corresponding to at least the space width between two teeth of the follower gear. The second cylindrical area 52-52' has a radius equal to the sum of the radius R of the follower gear, the width r of the eccentricity of the bearing surface in relation to the adjustment shaft and the necessary clearance between the gear and the surface. The portion 52-52' has its center of curvature coinciding with the center 48 of the adjustment shaft 32. The portions 54-52 and 52-52' merge into each other at the point 52 lying in the radial plane from the center 48 of the adjustment shaft through the center 50 of the follower gear in its extreme limiting position for maximum mesh. The cylindrical area 52'-56 has a radius slightly greater than the radius R of the follower gear and a center of curvature coinciding with the center 50' of the follower gear 22 when in its extreme limiting position for minimum mesh. The portions 52-52' and 52'-56 merge into each other at the point 52' lying in the radial plane from the center 48 of the adjustment shaft through the center 50' of the follower gear in its extreme limiting position for minimum mesh. Figs. 2 and 3 show the follower gear 22 contacting the first and third cylindrical area portions of the enveloping surface 44 respectively.

By varying the mesh variable volumetric capacity is effected with constant r.p.m. Rotation of the adjustment shaft 32 can be accomplished by means of a lever 58 and adjustments can be made by the application of positive force or by self-adjustment against a spring 60. Through a resilient actuation of the adjustment shaft a constant pressure is created after the pump, when it is possible to vary its capacity by applying various degrees of tension to the spring. The constant pressure is maintained in the area which is covered by the variation that is possible between the two limit stops. The pump maintains a certain pressure irrespective of the resistance in a certain area for the quantity variations allowed by the pump. The same variation can be achieved also by manual or comparable adjustment of the shaft when the pressure can be made to vary depending on the ability of the receiving collector tank to absorb fluid quantity at a certain pressure.

In the arrangement according to Fig. 1 it is possible to use the lever 58 for the adjustment of the follower gear within two stops limited by stop devices 62 and the resilient arrangement 60 for taking up the torque by means of which the adjustment shaft is actuated by the oil pressure.

In the form described in Figs. 1-4 the tooth profile is the involute type, which provides perfect mesh irrespective of the shaft spacing as long as sufficient quantity of teeth are meshing. In the above type the gears are further designed with helical teeth. In such helical gears it is possible to select the design in such a way that looking in the axial direction the front end of a following tooth profile is equal with the rear end of the preceding tooth profile. Due to the helical gears an improvement

is made by the fact that the teeth of the two gears always are in effective mesh with each other.

In Fig. 2 the direction of the gear rotation has been marked with arrows, just like the direction of the liquid flow when the arrangement is used as a pump. When used as a motor the flow direction of the medium is reversed. The same remark applies to the other illustrated designs. With an arrangement according to the design used as a motor constant torque is obtained within

10 a certain r.p.m. range.

In the arrangement according to Figs. 5-10 the drive gear 64 is of internal tooth type with unpierced tooth bases 66 and encased in the cavity created by the casing composed of the halves 70, 72. The gear race of the 15 drive gear 64 may be designed in one piece with a supporting part 74, to which the axle shaft 76 of drive gear 64 is connected, which axle shaft is supported in casing half 70. The follower gear 78 eccentrically supported is located inside the drive gear and its adjustment shaft 80 20 with eccentric bearing surface 82 for the follower gear is supported in casing half 72, where 84 indicates a bearing bushing. The adjustment shaft 80 is provided with an external lever 86 operating between the stops 88, 88' and the rotation of the adjustment shaft towards the extreme 25 limit stop corresponding to stop 88' occurs against the actuation of a spring 90.

To the adjustment shaft 80 a circular disc 92, concentric with said shaft, is attached which is supported in the casing half 72, i.e. on the opposite side of the gear elements in relation to the supporting part 74 for the external gear element 64. This disc 92 has on the high pressure side of the arrangement a sealing strip 94 projecting axially down into the intermediate space which contacts the tooth addendum circle of the internal gear 78. A stationary sealing strip 96 is attached to the casing half 72 and located in said intermediate space. The latter sealing strip 96 contacts externally the tooth addendum circle of the drive gear 64 and internally the outer edge of the sealing strip 94 contacting the follower gear 78, when the 35 sliding plane 98 between these two sealing strips is located along a circle concentric to the adjustment shaft 80, the diameter of which is equal to that of the disc 92.

The internal sealing strip 94 accordingly follows the adjustment shaft 80 when it is adjusted rotationally and 40 slides along the sealing surface 98 against the external stationary sealing strip. Figs. 5 and 10 show by way of comparison the reciprocal positions of the adjustable parts in full mesh of the gears and in the extreme limit stop, corresponding to maximum separation of the gears from 45 each other, respectively. For safety sake at least one of the sealing strips is provided with a packing 100 facing the joint between the sealing strips.

The disc 92 on the adjustment shaft 80 is provided with curved flow holes 102, 104 for the axial inlet and outlet 50 106, 108 of the operating medium of the pump (the designations inlet and outlet change place when the arrangement is used as a motor). At the rear of the supporting part 74 for the external gear race 64 a cavity 110 is located axially behind the flow hole 104 on the pressure 55 side of the arrangement and connected by means of ducts 112, 114, 116 with this flow hole in order to equalize the surface pressures (Figs. 7-8).

In this as well as in all other designs according to the invention the pressure component of the hydraulic pressure 60 on the pressure side, actuating the driven gear or the driven gear and the sealing strip, should always pass through the distortion center of the eccentric shaft on the side that provides a torque disengaging the gears. The bearing pressure resulting from the driven gear should always tend to rotate the eccentric shaft in such a way that the mesh of the gears will decrease when the arrangement is operating as a pump and the reverse when the arrangement is operating as a motor.

The arrangement shown in Figs. 11-12 is principally 65 of similar design as that described above in connection

with Figs. 5-10 differing from said arrangement only by the fact that the tooth bases of the external gear element 118 are pierced so that radial inlet and outlet holes 120 are created for the operating medium. For this reason the casing 122 of the arrangement should be provided with at least in principle radial inlets 124 and outlets 126 for the operating medium. Otherwise the details corresponding with the parts of Figs. 5-10 are designated with the same reference characters and in order to avoid repetition any further description of the same is not necessary. The axle shaft of the drive gear 118 is supported by means of needle bearings 128 in a bushing 130 arranged on the corresponding end of the casing 122. A pressure medium actuated operating mechanism 132 is provided for the mechanical operation of the lever 86 against the actuation of the spring 90.

Figs. 13 and 14 show the gear profiles of external and internal gear type with cut down tooth addendums 134 and 136, respectively, with the exception in this instance of the end parts 138 and 140, respectively, of the tooth addendums, which function as mesh guides for the co-rotation of the gears. At least one of the gears in each one of the arrangements described above can be provided with such a design due to which the arrangement has to be made larger in order to obtain desired capacity, but by means of which an increasing degree of variation is obtained with regard to the capacity of the arrangement, etc. In order to be able to get down to zero in regard to circulating quantity such an outlet is to be used.

In the diagram of Fig. 15 the pressure rise is shown as the function of the r.p.m. (*n*) of the pump when the curve η_{vol} constitutes the volumetric efficiency of the pump. The regulating range of the pump is indicated by means of a thick line, provided it works with a spring only for self-adjustment of the adjustment shaft against the effect of the liquid pressure in the pump discharge. By adding a servomotor, for example an electrically operated solenoid, hydraulically or pneumatically operated pressure plunger or similar power source, it is possible to apply a torque to the adjustment shaft. The size and direction of this torque may be optionally adjustable, whereby the various pressure regulating range curves are obtained, which are included in the diagram shown in Fig. 15. Accordingly above the curve for the spring alone are curves where the servo motor torque is added to the spring and below said curve characteristics in which the servo motor counterbalances the spring effect. The servo motor power and the spring power may be located either partially with each other as in Fig. 11 or located in series, whereby various types of characteristics are obtained.

In the regulating system according to Fig. 16 the arrangement is shown functioning as a pump by means of full-drawn lines. The lever 142 for adjustment of the adjustment shaft 144 for the eccentric bearing surface is retained by a spring 146 so that the gears are in maximum mesh. The pump discharge is connected with a pressure plunger 150 by means of a line 148. At rising pressure in the discharge the gears are accordingly separated from each other.

Thus it is possible to adjust the pump irrespective of the r.p.m. or r.p.m. variations and resistance variations within a certain range in order to provide constant pressure and the possibility of obtaining optional pressure. Principally constant pressure is obtained in certain areas and it is possible to select the pressure range from outside without having to by-pass any liquid quantity.

When the same arrangement is used as a motor, which is indicated by dash lines, the spring 146' works instead to separate the gears from each other, whereas the inlet of the motor is connected with the pressure plunger 150 via the line 148' in such a manner that the pressure plunger 150 will tend to increase the mesh between the gears.

In the control system according to Fig. 17 with the

arrangement applied as a pump its discharge may be connected either behind the pressure plunger 150 via line 148 or in front of the pressure plunger 150 via the line 148', when the change-over is made via a three-way valve 152. This means that in the diagram shown in Fig. 15 the curve scales ascend and descend, respectively, in relation to the base line for remote control only. A pressure variator 154 can be installed in the supply line to the pressure plunger 150 and for operating medium in the pressure plunger a separate medium in relation to the pump operating medium may possibly be used. The servo motor may be designed to be actuated from a distance by means for variation of the pressure in the supply line to the pressure plunger.

Fig. 18 shows a control system for a motor corresponding to the system in Fig. 17 for a pump. The spring 146' tends to separate the gears from each other, whereas the motor inlet by means of a line 148' is connected with the pressure plunger in such a manner that on rising pressure the gears assume a more close fit.

The control system in Fig. 19 for an arrangement according to the invention operating as a pump is provided with a servo motor in the form of a solenoid, the armature 156 of which is actuated by the coil 158. The coil 158 is fed from the circuit 160 and by means of a current changer it is possible to alternate the direction of the current and further control the amperage by means of a regulating resistor 164 for the purpose of moving the regulating range of the pump according to the principles as shown in Fig. 15.

What I claim is:

1. A rotary unit having a casing providing a chamber, a drive gear and a follower gear disposed in said chamber, said gears intermeshing with each other, an adjusting shaft angularly adjustably mounted in said casing in spaced relationship to the axis of said drive gear, said adjusting shaft being provided with a cylindrical bearing surface eccentric to the axis of said adjusting shaft, said bearing surface supporting said follower gear for adjustment of the intermesh between said gears by angular adjustment of the adjustment shaft, from one extreme limiting position in which the gears are in maximum mesh giving maximum capacity to a second extreme limiting position in which the gears are moved apart and are in minimum mesh giving minimum capacity, said chamber having a cylindrical surface in sealing relation with the outer periphery of the teeth of the drive gear and a non-adjustable enveloping surface in sealing relation with the outer periphery of the teeth of the follower gear, said casing having opposed radial high pressure and low pressure ports communicating with said chamber between said cylindrical surface and said enveloping surface with said surfaces terminating at said ports, said enveloping surface comprising one portion constituting a cylindrical area having a radius slightly greater than the radius of said follower gear and extending from said high pressure port, said portion having a center of curvature coinciding with the center of the follower gear when in its extreme limiting position for maximum mesh and having a length corresponding to at least the space width between two teeth of the follower gear, a second portion constituting a cylindrical area having a radius equal to the sum of the radius of the follower gear, the width of the eccentricity of the bearing surface in relation to the center of the adjusting shaft and the necessary clearance between the follower gear and the surface and with a center of curvature coinciding with the center of said adjusting shaft, said second portion merging into said first portion along a line lying in the radial plane from the center of said adjusting shaft through the center of said follower gear in the extreme limiting position for maximum mesh, and a third portion constituting a cylindrical area having a radius slightly greater than the radius of said follower gear and with a center of curvature coinciding with the

center of said follower gear when in extreme limiting position for minimum mesh, said third portion terminating at said low pressure port and merging into said second portion along a line lying in the radial plane from the center of said adjusting shaft through the center of 5 said follower gear when in extreme limiting position for minimum mesh.

2. A rotary unit as defined in claim 1, provided with a radially projecting handle for rotating the adjusting shaft.

3. A rotary unit as defined in claim 1, acting as a pump, which includes resilient means for automatic adjustment of the adjusting shaft against the action of the liquid pressure in the pump discharge.

4. A rotary unit as defined in claim 1 in which the 15 gears are of the external tooth type and are located side-by-side.

5. A rotary unit as defined in claim 1 in which the gears are of the involute type.

6. A rotary unit as defined in claim 1 in which it includes gears of helical shape.

7. A rotary unit as defined in claim 6 in which a front 20 end of a gear tooth profile is located in one and the same radial plane as the rear end of the preceding gear tooth profile.
